US00D731447S

(12) **United States Design Patent**
Ward et al.

(10) **Patent No.:** US D731,447 S
(45) **Date of Patent:** ** Jun. 9, 2015

(54) **THERMOELECTRIC ENERGY HARVESTER MODULE**

(71) Applicant: **Perpetua Power Source Technologies, Inc.**, Corvallis, OR (US)

(72) Inventors: **Marcus S. Ward**, Salem, OR (US); **Mark J. Hauck**, Corvallis, OR (US)

(73) Assignee: **Perpetua Power Source Technologies, Inc.**, Corvallis, OR (US)

(**) Term: **14 Years**

(21) Appl. No.: **29/433,005**

(22) Filed: **Sep. 24, 2012**

(51) LOC (10) Cl. **13-03**

(52) U.S. Cl.

USPC **D13/179**

(58) **Field of Classification Search**

USPC D13/110, 179; 165/80.3, 104.33, 151, 165/122, 185; 257/706, 707, 718-722; 361/695, 697, 700, 702, 704, 710, 711, 361/714

CLAIM

(57) The ornamental design for a thermoelectric energy harvester module, as shown and described.

DESCRIPTION

FIG. 1 is a side view of thermoelectric energy harvester module, showing our new design;

FIG. 2 is a bottom view thereof;

FIG. 3 is a top view thereof; and,

FIG. 4 is a perspective view thereof.

The broken lines in the drawings are included to show unclaimed subject matter only and form no part of the claimed design.
